UNITED STATES PATENT OFFICE.

MAURICE LACHMAN, OF NEW YORK, N. Y., ASSIGNOR, BY MESNE ASSIGNMENTS, TO LACHMAN MANUFACTURING COMPANY, OF NEW YORK, N. Y., A CORPORATION OF DELAWARE.

SHIPPING-RECEPTACLE.

1,147,954.

Specification of Letters Patent.

Patented July 27, 1915.

Application filed October 22, 1910. Serial No. 588,417.

To all whom it may concern:

Be it known that I, MAURICE LACHMAN, a citizen of the United States, and a resident of New York, in the county of New York 5 and State of New York, have invented certain new and useful Improvements in Shipping-Receptacles, of which the following is a specification.

My present invention relates to receptacles 10 or packages for shipping various articles such as fruit, hardware or goods of any nature whatsoever.

The main object of the invention is to provide a receptacle light in weight but capable 15 of rough handling and which will be of a knock-down type so that, when empty, the receptacles can be stored in a very small space and can be shipped at very low rates owing to the compactness with which the 20 parts can be bundled together.

Another object is to secure a very cheap construction in a knock-down shipping package and which can be readily and quickly assembled when desired to use the 25 package. This cheapness in construction is attained without sacrificing strength and when the parts are assembled the receptacle is as rigid as though it was not of the knock-down type.

30 Heretofore by known methods it has not been practical to construct a knock-down type of shipping package in large sizes nor to apply the knock-down idea to receptacles in which it was desired to forward heavy 35 weights but such receptacles had to be made and assembled complete in the factory in order to insure the necessary strength or weight-carrying capacity.

Owing to the increasing cost of wood, and 40 the heavy material necessary to stand the rough handling in shipping, I preferably employ paper sections and reinforce them with metal strips whereby a very much lighter package is attained than could possibly be used to ship the same weight of 45 goods in a wooden receptacle and in so far as I am aware such a structure in a knock-down package has heretofore not been conceived or constructed in the manner set forth 50 in the appended claims.

The invention consists in the improved construction of knock-down shipping receptacle hereinafter more particularly described and then specified in the claims.

In the accompanying drawings Figure 1 55 illustrates a side elevation of a cylindrical receptacle constructed in accordance with my invention. Fig. 2 is a plan view of the same. Fig. 3 is an enlarged central section of one end of the receptacle, the section being taken on the line of junction of two of the separate sections making up the body portion of the receptacle. Fig. 4 is a side elevation of one of the detached sections. Fig. 5 is an enlarged horizontal section on 60 the line X X Fig. 4. Fig. 6 is a plan view 65 of a rectangular form of receptacle constructed in accordance with this invention. Fig. 7 is a side elevation of one of the detached sections of the form illustrated in 70 Fig. 6. Fig. 8 is an edge view of the same. Fig. 9 is a vertical section taken on the line Y Y Fig. 6 showing only the upper part of the receptacle. Fig. 10 is a horizontal section on the line Z Z Fig. 7. Fig. 11 illustrates 75 a modification in the manner of joining the sections together.

The receptacle is made up of a plurality of individual sections or parts forming the body portion and the heads or closures 80 secured to the body portion and closing in the receptacle.

The body portion consists of a plurality of separate independent sections and in the forms illustrated four sections are employed 85 but, it will be understood that the body might consist of any number of sections desired varying, as a rule, according to the size and character of the receptacle. In the form shown in Figs. 1 to 5 inclusive, each 90 section is made up as a quadrant so that when joined together along their longitudinal edges they form a cylindrical body portion as shown in Fig. 2. Each section consists of a sheet or plate of continuous, 95 preferably imperforate, material such as heavy paper or cardboard 1 made up preferably by compressing and solidifying a number of superimposed layers of paper in a manner now well known in paper making. 100

Located at each side edge of the material 1 are metallic stay members 2, 3 each provided with a number of longitudinally disposed inwardly projecting ears or flanges 4 and a number of outwardly projecting 105 ears or flanges 5. These ears are preferably formed in a staggered manner from the material of the stay member by slitting the

edge of the strip and bending one section of the metal one way and its neighbor in the opposite direction and so on in an obvious manner. The paper plate 1 is placed 5 against the inner surface of the stay members 2, 3 and the ears 4 bent around the edge of the plate and engage the opposite surface of the plate 1 thereby fastening the stay members to the paper plate. Preferably the stay members 2, 3 are part of a framework made by connecting the stay members by bands 6, 7 preferably welded at 10 8 to the stay members at or near both ends.

The bands 6, 7 are each provided with an 15 inwardly projecting flange which engages the upper and lower edge respectively of the material 1 thereby serving with the flanges or ears 4 to inclose and effectually hold the material 1 to the reinforcing framework 20 whereby a retaining frame is formed in which the material is inclosed and held. In making up the section the framework is 25 preferably first constructed by welding the stay members and bands together, as described, after which the plate 1 is placed in position between the flanges of the bands and the ears 4 folded over. If desired, further reinforcing means might be employed such as one or more bands 9 secured to the 30 stay members 2, 3, preferably by welding the ends thereto at points between the bands 6 and 7. Also additional stay members might be employed between the members 2 and 3 although if employed it will be obvious they would not need to be provided with 35 the ears or flanges 4, 5.

The ends of the stay members 2, 3 are elongated beyond the outer edges of the bands 6 and 7, thereby forming ears 10 by 40 means of which the heads or closures for the body portion are secured thereto in a manner to be presently described.

11 indicates a coupling piece or connecting strip provided with an inturned flange 45 at both longitudinal edges, each of which engages the outwardly projecting ears or flanges 5 of the stay members, the ears of the member 2 of one section being connected to the ears of the member 3 of the next section by the coupling piece 11 when joining the sections together to form the body portion of the receptacle. The sections are joined together by presenting the edges of 50 two sections together and slipping the coupling pieces endwise over the flanges 5 of the stay members. If desired after the coupling piece is in place the flanges might be pinched with a pair of pliers or otherwise to prevent accidental withdrawal.

60 It will be noted that the strain at the junction of the sections is taken by the reinforcing means and not by the material 1. The framework of each section is joined to that of the next section whereby a body portion is attained having a rigid and connect-

ed reinforcement, none of the strain of holding the sections together falling on the material 1.

The body portion is provided with upper and lower heads or closures. Each head 70 consists of an annular ring 14 provided with an outwardly projecting flange 15 at its outer edge and an inwardly projecting flange 16 at its inner edge. Seated on the inwardly projecting flange 16 is a disk 17 75 preferably of heavy paper and held in place by a plurality of ears 18 cut out of the material of the ring 14 and bent over to engage the surface of the disk 17 opposite the flange 16. If desired, the head may be reinforced by a second disk 19 glued or otherwise secured to the disk 17 and also, if desired in some cases, metal reinforcing strips or lattices might be superimposed on the disk 17 and the ends of the strips welded or 80 otherwise secured to a suitable part of the ring 14.

The head is placed on the body portion, the ring 14 fitting inside the body and the flange 15 seating on the end of body as 90 shown, after which the projecting ears 10 of the stay members 2, 3 are bent over and clamp the head to the body.

In the forms shown in Figs. 6 to 10 inclusive, each section is formed as a flat rectangle, the material 1 being reinforced by the framework consisting of the stay members 2, 3 and the bands 6 and 7 as heretofore. In this case two intermediate stay members 2', 3' are employed owing to the large 100 area of flat paper 1 used as the inclosing medium. The reinforcing metal strips might be further strengthened by raising ribs 20.

In this form the outwardly projecting 105 flange 5 is shown as continuous and the material 1 held on the other side by ears 21 cut from the material of the stay members. Except that they are rectangular in form the heads are formed in the same general 110 manner as before and secured by the projecting ears 10 of the stay members.

As shown in the modification Fig. 11, the separate coupling piece 11 for joining the sections may be dispensed with and the outwardly projecting flanges so formed as to lock one over the other as for instance by forming one into a hook 22.

What I claim as my invention is:

1. A knock-down receptacle comprising a 120 plurality of non-metallic sections forming the body portion, a retaining framework for each section comprising reinforcing stay members, longitudinally disposed flanges on said stay members, coupling pieces adapted to engage said flanges and join the individual sections together, closures for the ends of said receptacle and ears integral with said stay members for fastening said closures to said body portion. 125 130

2. A section for a knock-down receptacle comprising a blank of non-metallic material, a plurality of which are necessary to complete the receptacle, a metal framework retaining and inclosing said material and comprising stay members located at the side edges of said material and provided with ears adapted to hold the material to said members, bands located at the other edges of said material and secured to said stay members, said bands being provided with ears or flanges adapted to engage the edge of the material and outwardly projecting flanges on said stay members whereby two sections may be joined together, said stay members extending beyond said bands to afford fastening means for the heads of the receptacle.
3. As an article of manufacture a section for a knockdown container having a body portion comprising a sector of a paper cylinder, metallic stays at each edge of said sector, ears from said stays bent around the edge of said body portion, metallic end bands having flanges extending over the ends of said body portion, said metallic end bands being secured to said metallic stays to retain the same in position on said body portion, said metallic members hereinbefore recited comprising a sustaining framework inclosing said sector, and securing means on said edge stays to enable adjacent sections to be secured together.
- 5 10 15 20 25 30 35
- Signed at New York in the county of New York and State of New York this 7th day of October A. D. 1910.
- MAURICE LACHMAN.
